WINDOW VENTILATOR

Charles L. Casey, Chicago, Ill.

Application June 14, 1939, Serial No. 279,068

3 Claims. (Cl. 98—99)

This invention relates to improvements in window ventilators of the type which is adapted to be secured within the window frame in a position that it will not interfere with the opening or closing of the window, and one of the objects of the invention is to improve and simplify the construction of such ventilator and at the same time provide a simple, effective and inexpensive device of this character.

A further object is to provide in an improved ventilator of this character improved means for securing the same in position whereby it may be readily removed and as readily replaced.

A further object is to provide an improved adjustable ventilator of this character which is also of a knock-down or collapsible construction for shipment and storage purposes.

A further object is to provide an improved combined ventilator and screen which latter may be readily removed and as readily placed in position without interfering with or removing the ventilator from the window.

A still further object is to provide an improved screen attachment for a ventilator of this character and which screen is readily adjustable to fit windows of various sizes.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a perspective view of a ventilator of this character, constructed in accordance with the principles of this invention and showing the same as applied to a window frame.

Figure 2 is an elevation on an enlarged scale, of one of the end members before the body member or screen are secured thereto.

Figure 3 is a detail sectional view, on an enlarged scale, as taken on line 3—3, Figure 1.

Figure 4 is a detail sectional view taken on line 4—4, Figure 1.

Figure 5 is a detail perspective view, on an enlarged scale, of one of the end members.

Figure 6 is a detail sectional view on an enlarged scale, taken on line 6—6, Figure 1.

Figure 7 is an enlarged detail sectional view taken on line 7—7, Figure 4, with parts omitted.

The ventilator consists essentially of end members 10 of any desired size and configuration but are preferably substantially triangular, the upper

end 11 being of a greater length than the lower end 12.

These end members may be constructed of any suitable material but are preferably formed of metal of a comparatively thin gauge, and in order to impart rigidity thereto there may be provided a peripheral reinforcing flange 13.

The front edge 14 of each of the end members is preferably inclined to the vertical and there is provided a laterally projecting seam 15 formed by bending a portion of the edge back upon itself to provide a channel or groove 16 that extends for substantially the length of the edge 14 but terminates a short distance from the flange 13.

A portion of the seam 15 may be shaped to provide a lip or projection 17 which initially projects below the lower edge 12 of the end member.

Two of these end members are provided and each is also provided with a keyhole slot 18 in its body, suitably located.

The body of the ventilator is formed of two members 19—20 also constructed of any suitable material but preferably metal arranged in overlapping relation. The upper edge of one of the members, such as the member 20 may be shaped to provide a tubular formation 21, the edge of such formation being spaced from the body portion 20 to form an opening 22.

The upper edge of the body member 19 may also be shaped to provide a tubular portion 23 which telescopes into the tubular portion 21, and a portion of the body member 19 passes through the opening 22 so that these two members will be adapted for free longitudinal relative adjustment.

The lower edge of the body members 19—20 may be shaped to form channels 24—25 one of which fits within the other for sliding relation, and serves to prevent lateral separation of the body members 19—20 at the lower edge thereof.

The free extremity of each of the body members 19—20 is bent back upon itself as at 26, and this portion 26 is adapted to telescope into the groove 16 of the seam 15 of the adjacent end member 10 thereby forming a telescoping or adjustable seam connection between the respective end members and the proximate end of the adjacent body member.

With this construction it will be manifest that the end members may be detachably connected to the body members, so that they may be separated therefrom and the ventilator may be collapsed or knocked down, and may as readily be assembled.

In order to prevent separation or detachment of the end members from the respective body members, the projection or extension 17 on the

end members may be provided, and this projection is adapted to be flanged or bent over the lower edge of the respective body member, as shown more clearly in Figure 3 of the drawing.

The projection 17 co-operates with the reinforcing rib or flange 13 to lock the parts together as the extremity of the tubular formation at the upper edge of the respective body members 19-20 will pass under the flange 13, as shown more clearly in Figs. 3 and 6, and will hold the body member against being raised with respect to the end member while the lip or projection 17 will hold the body member against being lowered with respect to the end member.

Furthermore, the extremities of the body members 19-20 passing under the respective adjacent flanges 13 will be concealed and the space between the body member and the end member will be closed by the flange 13.

When, however, it is desired to detach the end member from the body member, this projection 17, if employed, may be bent back into its normal position or out of the way so as to permit such detachment.

When the parts are thus assembled the ventilator may be secured in position and to a window frame by means of a headed screw or bolt 21 which passes through the keyhole slot 18, thereby providing a means which will permit of ready detachment of the ventilator from the window frame.

Two of the fastening elements 21 are all that are necessary as the keyhole slots 18 are so positioned in the end members that when the head of the screw is passed through the enlarged portion of the slot, the end members and ventilator may be dropped down until the bottom 12 of the end member rests upon the window sill. This will maintain the ventilator from swinging about the fastening devices 21.

Associated with the ventilator is a screen embodying two perforated or reticulated members 28-29 adjustably secured together by flanging the top and bottom edges 30-31 of the member 28 over the adjacent edge of the body member 29. These members may be of any desired width but are preferably of a width substantially equal to the height of the end members 10. The outer extremity of each of the screen members is shaped to form a laterally projecting flange 32 and secured to the face of each of the members 28-29 adjacent and within the respective flanges is a member 33. The member 33 terminates short of the adjacent flange 32 and a space 34 is formed between the members 33 and the respective screen members 28-29.

An upright flange 35 is provided along the rear edge of the respective end member 10 and this flange terminates short of the flange 13 to form a space 36 at the upper rear corner of each end member 10.

This space is provided to permit the screen to be placed in position by inserting the flange 35 in the respective spaces 34 between the member 33 and the screen member from the lower edge of the screen members.

When placing the screen in position the flange 35 will not only enter the space 34 but a portion of the end member 10 will enter the space between the extremity of the member 33 and the adjacent flange 32 of the screen member. This will provide a sliding mounting for the screen and renders it possible to place the screen in position and as readily remove the same.

When in position the screen will be disposed in

close proximity to the window but it will not interfere with raising or lowering the window.

Furthermore as the screen is secured to the end members and is adjustable in a manner similar to the body members 19-20 of the ventilator the size of the ventilator and screen may be varied by adjusting the end members 10 laterally with respect to each other.

With this improved construction it will be manifest that the ventilator is not only adapted to be readily detached from the window frame without the adjustment of any screws or fastening devices but at the same time is adapted for adjustment to fit windows of varying widths.

While the preferred form of the invention has been herein shown and described, it is to be understood that various changes may be made in the details of construction and in the combination and arrangement of the several parts within the scope of the claims without departing from the spirit of this invention.

What is claimed as new is:

1. A window ventilator embodying end members, a guideway along the front edge of each of said end members, a body portion embodying overlapping sections slidably connected together, means at the outer ends of said overlapping members and slidably in said guides, a flange at the rear edge of the end members, a screen embodying overlapping reticulated members slidably connected together, a flange on each of the screen members contacting the outer face of the respective end members, the flange on the end members contacting the face of the screen member, a securing member connected to the screen member and overlapping the flange on the end member whereby the flange on the end member will be disposed between the screen member and the said securing member and a portion of the end member will be disposed in a space between the flange in the screen member and the adjacent edge of said securing member, and means for detachably securing said end members to a window frame.

2. A window ventilator embodying end members each of which is provided with a continuous lateral projecting flange extending along one of the sides and top thereof, the portion of the flange extending along the front edge of the end members being of a width considerably greater than the adjacent portion of the flange which extends along the top of the end member and being bent back upon itself to form a guide terminating short of the top flange, a body portion embodying overlapping members secured together for free relative longitudinal adjustment, the free ends of the last said members being bent back to form guides, the free ends of the body members and the said end members being adapted to be connected together by causing the guides of the body members and the end members to interengage, the flange on the adjacent portion of the end members overlapping the ends of the body members, a projection at the base of the end members foldable over the adjacent edge of the proximate body member for locking the parts together, and means for securing the end members to the window frame for detachment therefrom.

3. A window ventilator embodying end members each of which is provided with a continuous lateral projecting flange extending along both sides and top thereof, the portion of the flange extending along the front side of the end members being of a width considerably greater than the adjacent portion of the flange which extends

along the top of the end member and being bent back upon itself to form a guide terminating short of the top flange, a body portion embodying overlapping members secured together for free relative longitudinal adjustment, the free ends of the last said members being bent back to form guides, the free ends of the body members and the said end members being adapted to be connected together by causing the guides of the body members and the end members to inter-engage, the flange on the adjacent portion of the

end members overlapping the ends of the body members, a screen member formed of co-operating extensible sections, a guide along the free end of the respective screen sections and into which guides the flange which is along the rear side of the end member projects, the last said flange terminating short of the top flange of the end member, and means for securing the end members to the window frame for detachment therefrom.
